[57] ABSTRACT

A condenser shell structure having a trough formed by an inner wall spaced from the outer shell structure and extending upwardly from the condenser support plane to a region adjacent the flange connection with the exhaust duct of a steam turbine operable at variable exhaust temperature. The trough is continuously provided with condensate from the condenser hot well at approximately saturation temperature, thereby to maintain the condenser shell temperature at saturation temperature for the exhaust steam pressure with attendant minimization of thermal growth of the condenser shell.

The turbine may thus be supported by the condenser with minimal movement of the turbine that could otherwise cause misalignment of associated gearing and coupling members.

FIG.4

APPARATUS FOR CONTROLLING THERMAL GROWTH IN CONDENSERS

BACKGROUND OF THE INVENTION

It has heretofore been the usual practice by the assignee of this invention, in the marine turbine art, to support the steam turbine on a base or pedestal structure and hang the steam condenser from the turbine. With this arrangement, temperature excursions of the condenser shell occasioned by the wide range of turbine exhaust temperature attained during operation, with attendant thermal growth, could have little if any effect on the turbine mounting position. Accordingly critical alignment of the turbine shaft with its associated gearing and coupling members could be maintained during such wide range of temperature.

However, marine turbine horsepower ratings are constantly increasing with attendant increase in size and weight of the turbine and the condenser. Supporting the heavier condenser is becoming a significant problem, particularly with respect to the interface connection between the turbine and the condenser.

Accordingly, it is desirable to mount the turbine on the condenser. However, such an arrangement creates a difficult problem with regard to alignment of the turbine and its driving connection with the reduction gearing, since thermal growth of the condenser shell will inherently shift the turbine out of its axially aligned position with respect to the gearing and shaft coupling members.

SUMMARY OF THE INVENTION

In accordance with the teachings of this invention, there is provided a marine turbine and condenser structure in which the turbine is mounted on the condenser shell and supported thereby. The condenser shell structure has an internal trough formed adjacent the condenser support plate and extending upwardly to a region adjacent its steam inlet flange, which inlet flange is connected to the steam exhaust structure flange of the turbine.

The trough is continuously provided with water during operation, and is maintained at or near the saturation temperature for the steam at the exhaust pressure. The shell of the condenser is thus held at the temperature of the water by direct contact therewith. Thus, even though the turbine may be exhausting at a high temperature (as when driving in the astern direction) but at low pressure (due to total heat load and condenser characteristics) the condenser shell temperature will be maintained substantially at the saturated steam temperature for the prevailing condenser pressure and will not be strongly influenced by the high temperature of the exhausting steam.

The water for the trough is preferably condensate from the condenser hot-well which is maintained near the saturation temperature for the prevailing low condenser pressure. Excess condensate is continuously drawn off, preferably by overflow conduit means and returned to the hot-well of the condenser. Hence, the overflow is prevented from falling onto the condenser tubes or being picked up by the high velocity of the incoming turbine exhaust steam.

DESCRIPTION OF THE DRAWINGS

FIG. 1 is an end view of a steam turbine supported by a condenser having one embodiment of the invention

incorporated therein, with portions cut away to show internal structure of the condenser;

FIG. 2 is a longitudinal view of the steam turbine shown in FIG. 1 with the condenser in cross-section;

FIG. 3 is an enlarged fragmentary view of the upper right-hand portion of the condenser, as viewed in FIG. 2, to show details of the internal trough structure; and

FIGS. 4 and 5 are views similar to FIGS. 1 and 2 but showing another embodiment of the invention.

DETAILED DESCRIPTION OF THE PREFERRED EMBODIMENT

Referring to the drawings in detail, FIGS. 1 and 2 show a first embodiment of the invention in which a steam turbine 10 is provided with a steam condenser 12 incorporating the invention. The turbine shown in the example is a marine propulsion turbine of the low pressure type, which, as well known in the art, is supplied by motive steam after partial expansion in a high pressure turbine (not shown). The turbine 10 has an output shaft 14, which is drivingly connected to a ship's propeller through reduction gearing by a suitable coupling (not shown).

The turbine 10 has a steam inlet 15 for driving the turbine shaft in the ahead mode, i.e., in a direction to propel the ship forward, and an alternately employed steam inlet 16 for driving the turbine shaft 14 in the astern mode, i.e., in a direction to propel the ship rearward.

The turbine 10 is of the condensing type, i.e., after the energy of the motive steam is dissipated by the turbine, the spent steam is directed through an exhaust outlet 18 into the condenser 12.

The condenser 12 is of the tube-and-shell type and includes a condenser outer shell structure 20 having a bundle of heat-exchange tubes 21 disposed therein and extending therethrough in a direction transverse to the axis A of the turbine 10. The tubes are received at their opposite ends in suitable tube sheets 22 and 23 which together with suitable channel heads 25 and 27 form respective inlet and outlet water chambers 28 and 29 disposed in fluid communication with the tubes 21.

The channel head 25 is provided with an inlet nozzle 30 and the channel head 27 is provided with an outlet nozzle 31. Coolant water, from any suitable source (not shown) such as the sea is admitted to the inlet nozzle 30, from whence it flows into the inlet chamber 28 and thence through the tubes 21 to the outlet chamber 29. During its flow through the tubes 21, the coolant water removes heat from the turbine exhaust steam thereby condensing it. The thus heated coolant water is then directed from the outlet nozzle 31 back to the sea.

The condenser shell structure 20 is provided with a sump or hot-well portion 33 at its bottom end to collect the condensate, and an outlet conduit 34 is provided at the bottom of the hot-well 33 for removing the condensate from the condenser. A pump 35 of any suitable type is interposed in the outlet conduit 34 for pumping the condensate back to a suitable steam generator (not shown) for re-vaporization.

As best shown in FIG. 2, the condenser 12 is disposed in an opening 36 in a ship's structure 37 and suspended therein in a support plane P-P extending through the upper portion of the outer shell 20 by a pair of condenser support structures 40. The condenser support structures 40 are disposed externally of the outer shell

walls 41 and 42 and each comprise a lower horizontal flange member 43, an upper horizontal flange member 44 and a plurality of spaced reinforcing gussets 45. The lower flange 43 bears on the upper surface of the ship's structure 37 to support the condenser thereon, while the upper flange 44 bears on the bottom of the turbine casing flange 40 to support the turbine 10 thereon.

With the above arrangement, the entire weight of the turbine 10 is supported by the portion of the outer shell structure 20 of the condenser lying between the lower flange 43 and the upper flange 44. Accordingly, the vertical position of the turbine shaft 14 is influenced considerably by the thermal expansion characteristics of the condenser outer shell structure during a heating period when the turbine 10 is in operation, taking as a point of reference, the "at rest" period when the turbine is not in operation and the temperature of the outer shell structure is at ambient temperature.

The critical portion of the outer shell structure 20 is that peripheral portion 47 lying between the upper and lower support flange members 44 and 43, respectively.

In accordance with the invention, in order to minimize the thermal growth of the outer shell portion 47, an inner wall structure 50 is connected to the outer wall member 42 by a bottom wall member 51, thereby providing an elongated open water passage or trough 52 communicating with the interior 53 of the condenser.

As best shown in FIGS. 1 and 3, a distribution plate 55 is attached to the outer wall 42 but is disposed in slightly spaced relation with the inner wall 50. If desired, the distribution plate 55 may be provided with a plurality of spaced perforations 56. The distribution plate is disposed in an intermediate position in the trough 52, and a flanged connector 57 inserted in the outer condenser shell 20 provides an inlet 58 for water into the trough 52 below the distribution plate 55, as will be subsequently described.

Also, to prevent entrance of high velocity steam into the trough 52, an inclined baffle plate 60 is attached to the outer wall 42 and disposed in a manner to extend across the inner wall member 50.

In the example shown and described above, the outer shell wall 42 is a planar member extending vertically. Hence, the inner wall portion 50 is also planar and vertically disposed to impart a uniform cross-sectional shape to the trough 52.

However, the outer shell wall 41 has an upper portion 61 (FIG. 2) inclined inwardly at an angle of about 45°. Accordingly, in this portion an inner wall member 62 is provided with an inwardly inclined upper portion 63 conforming to the outer wall portion 61, thereby to provide an elongated trough 65 of uniform cross-sectional shape in this portion of the condenser. Here again, an inclined baffle plate 66 (similar to baffle plate 60) is arranged to extend across the inner wall portion 63 to prevent admission of high velocity steam into the trough 65.

A second flanged connector 57a inserted in the outer wall 41 may be provided to admit water into the trough 65.

As best shown in FIG. 1, the opposite ends of the trough 52 are terminated and defined by a pair of transverse wall members 67 and 68 connected at their bottom portion to the bottom plate 51 and at their upper portion to the peripheral shell portion 47.

The trough 65 is terminated at its ends in a manner similar to the trough 52 in a manner which is now clear and need not be shown.

The inlet connectors 57 and 57a are connected by 5 parallel conduits indicated by 70, 71 to the discharge end of the pump 35, so that in operation a part of the condensate usually returned to the steam generator is supplied to the troughs 52 and 65.

In operation, as the vitiated steam from the turbine 10 is condensed in the condenser 12, it drops to the hot-well 33 where it is withdrawn through the conduit 34 by the pump 35 for delivery to the steam generator (not shown) for re-evaporation and returned to the turbine 10 as motive steam in a closed cycle, as well 15 known in the art.

However, a portion of this condensate is delivered to the troughs 52 and 57 by the conduits 70 and 71 and admitted thereto below the distribution plate 52. As the water level rises in the trough, it passes around the distribution plate 55 and through the perforations 56 to substantially fill the trough. To prevent spill-over of the water into the steam flow path and to prevent impingement directly onto the surface of the condenser tubes 21 one or more overflow pipes 73 may be attached to 25 the inner wall 50. And in a similar manner, one or more overflow pipes 74 may be attached to the inner wall 62. The pipes 73 and 74 extend along the outer boundary of the tube bundle B (FIG. 2) and downwardly therepast to direct such overflow directly to the hot-well 33.

Since the condensate from the hot well is constantly provided to the troughs 52 and 65, and since this condensate is approximately at saturation temperature for the low pressure conditions in the condenser, the outer shell 20 of the condenser is maintained at the temperature of the condensate in the condenser regardless of the temperature of the exhaust steam before condensing. Thus, even when the turbine may be exhausting at a high temperature (as when going astern) but at low pressure (due to total heat load) the condenser outer shell will be maintained at the saturated steam temperature for the pressure. Accordingly thermally induced growth of the outer shell is minimized, at least in the region between the mounting plane P—P' and the turbine mounting flange 44, thereby substantially eliminating any movement of the turbine 10 that could otherwise cause misalignment of the turbine shaft 14 and its associated gearing and coupling members.

In FIGS. 4 and 5 there is shown another embodiment of the invention. This embodiment is generally similar to the first embodiment described above. However, in this embodiment the turbine 10 is mounted upon and supported by a condenser 75 which, in turn is mounted upon and supported at its bottom end by a foundation structure 77.

It will be noted that with this arrangement the entire outer shell structure 78 of the condenser 76 is disposed between the condenser mounting plane MP—MP' and the turbine exhaust flange 80. Accordingly the entire shell is susceptible to thermal growth, in operation, with attendant undesirable misaligning movement of the turbine.

In accordance with the invention, thermal growth of the outer shell 78 is minimized by provision of a pair of vertically elongated trough structures 80 and 81 that extend from the hot-well 83 upwardly substantially to the condenser mounting flange 84.

As in the first embodiment, the troughs 80 and 81 are disposed in transversely opposed relation (see FIG. 5) on opposite sides of the tube bundle 85 and defined by the outer side walls 86, 87 of the condenser shell and inner spaced walls 88, 89, respectively.

Accordingly, in this embodiment, the troughs 80 and 81 hold a body of hot-well condensate that extends for substantially the entire vertical extent of the condenser outer walls 86 and 87.

In all other respects, this embodiment may be similar to the first embodiment and need not be further described.

It will now be seen that the invention provides an arrangement in which the outer shell structure of a steam condenser is prevented from overheating in an unpredictable manner and in which the thermal growth is controlled in operation to a predictable minimum degree of expansion.

It will further be seen that with the above arrangement, the turbine may be mounted upon the condenser and supported thereby, with full assurance that deleterious movement of the turbine, during a wide range of operation, is minimized.

It must further be pointed out that in both embodiments the troughs or water passages are on opposite sides of the tube bundle and substantially coextensive therewith. The end portions of the condenser outer shell structure do not necessarily require the trough treatment for two reasons, first, the coolant water in the channel heads and tubes provide an optimum heat sink for the adjacent portions of the condenser shell structure, and, second, the end portions of the shell are not normally in line between the shell support 17 or 37 and turbine 10, so that thermal growth would not influ-

ence the turbine location.

We claim:

1. In combination, a steam turbine, a condenser for condensing steam exhausted from said turbine, said condenser having a shell structure and an exhaust structure connecting said condenser shell structure to said turbine, said turbine being adapted to exhaust steam to said condenser at varying temperatures, a condensate pump for removing condensate from said condenser, an upwardly extending inner wall joined to one of said structures to jointly form therewith a water wall in fluid communication with the interior of the condenser and with said condensate pump, and overflow means associated with said water wall, whereby condensate is circulated in said water wall to maintain the temperature of said one structure generally at a temperature equal to that of the condensate regardless of the temperature of the exhaust steam.

2. The combination recited in claim 1, wherein the condenser comprises a plurality of heat exchanger tubes for condensing the turbine exhaust steam, a hot well for collecting the condensate and means for directing condensate from said overflow means to said hot well.

3. The combination recited in claim 1, wherein the one structure is the exhaust structure.

4. The combination recited in claim 1, wherein the one structure is the condenser shell structure.

5. The combination recited in claim 1 and further comprising a distribution plate disposed in said water wall to distribute the condensate over the entire water wall.
